UNITED STATES PATENT OFFICE.

ANTHONY T. WRIGHT, OF FROLONA, GEORGIA.

SHOE-FASTENER.

1,211,996.

Specification of Letters Patent.

Patented Jan. 9, 1917.

Application filed December 29, 1914. Serial No. 379,495.

To all whom it may concern:

Be it known that I, ANTHONY T. WRIGHT, a citizen of the United States, residing at Frolona, in the county of Heard and State 5 of Georgia, have invented certain new and useful Improvements in Shoe-Fasteners; and I do hereby declare the following to be a full, clear, and exact description of the invention, such as will enable others skilled 10 in the art to which it appertains to make and use the same.

This invention relates to improvements in shoes, and more particularly to a simple and quickly and easily operable shoe fastener for detachably securing the meeting edges of the shoe together.

The invention has for its object to provide a shoe fastener including a flexible member rotatably secured longitudinally of 20 one of the edges of the shoe carrying a plurality of spring hook members adapted to engage eyelets in the other edge to secure the edges in position on the wearer.

With this and other objects in view, the 25 invention consists in the novel construction, arrangement and formation of parts as will be hereinafter specifically described, claimed and illustrated in the accompanying drawing, in which:

30 Figure 1 represents a front elevation of a shoe showing the improved fastener applied thereto. Fig. 2 represents an enlarged detail sectional view on the line 2—2 of Fig. 1, and Fig. 3 represents an enlarged detail view, partly in section, of the bearing member for the rotatable part of the fastener.

Referring to the drawing in detail, wherein similar reference numerals designate corresponding parts throughout the several 40 views, the numeral 5 indicates generally a shoe of any preferred construction having one edge 6 of the upper provided with a plurality of eyelets 7. A rotatable member 8 is secured longitudinally of the other edge 45 9 of the shoe upper and is rotatably secured in bearing members 10 having apertures receiving the reduced end portions 11 of the rotatable member 8 and having integral spaced tongues 12 whereby the bearing members are secured in position upon the shoe 5.

A plurality of hook members 13 preferably formed of spring material and corre-

sponding in number to the number of eyelets 7 in the edge 6 are secured eccentrically to 55 the member 8 and are provided with hooked ends 14 adapted to engage within the eyelets 7 of the edge 6. The beaks or hooked ends of the hook members are of adequate strength and rigidity to prevent them from 60 straightening out and slipping through the eyelets 7. It will be understood that the rotatable member 8 is curved from end to end so that it will lie flat against the shoe and said member is preferably formed of a resilient metal. An arm or handle 15 is secured centrally of the rotatable member 8 and is adapted to engage the adjacent portion of the shoe upper to prevent rotation of the member 8 when the shoe is in use and 65 the hooked ends 14 of the hook members 13 are engaged within the eyelets 7. When it is desired to remove the shoe the arm or handle 15 is moved upwardly to the dotted line position in Fig. 2, thus moving the hook 70 members 13 longitudinally and drawing the edges of the shoe closer together, and by holding the shoe edges in this relatively close relation and swinging the arm or handle 15 to its initial position against the shoe, 75 the hooked ends or beaks of the hook members 13 may be readily withdrawn from the eyelets 7 after facilitating removal of the shoe.

What I claim is:

The combination with the curved meeting edges of an article of wearing apparel, of a plurality of eyelets secured to one of the edges, a pair of bearing members secured to the other edge, a member longitudinally secured in said bearing members and curved from end to end conformably with the curved meeting edge, a plurality of spring hook members secured to said rotatable member and having hooked outer terminals adapted to engage in said eyelets, and an arm secured to said rotatable member adapted to engage a portion of the article of wearing apparel to secure the rotatable member against rotation.

In testimony whereof I affix my signature in presence of two witnesses.

ANTHONY T. WRIGHT.
